P. A. KINZIE.
FUEL FEEDING APPARATUS.
APPLICATION FILED JUNE 10, 1921.

1,424,486.

Patented Aug. 1, 1922.

UNITED STATES PATENT OFFICE.

PHILLIP ALEXANDER KINZIE, OF LITTLETON, COLORADO.

FUEL-FEEDING APPARATUS.

1,424,486.

Specification of Letters Patent. Patented Aug. 1, 1922.

Application filed June 10, 1921. Serial No. 476,597.

To all whom it may concern:

Be it known that I, PHILLIP ALEXANDER KINZIE, a citizen of the United States of America, residing at Littleton, county of 5 Arapahoe and State of Colorado, have invented a new and useful Fuel-Feeding Arapahoe, and State of Colorado, have in specification.

My invention relates to a new automatically operating pressure feeding apparatus for the gasoline or other fuel used in internal combustion engines.

And the objects of my invention are:

First. To provide a pressure feeding apparatus that will force the gasoline or other fuel into the carburetor by air pressure and that will automatically regulate the pressure of the air.

Second. To provide a pressure feeding apparatus for internal combustion engines that is so connected to one of the cylinders of the engine that the explosions in that cylinder will act to pumpingly compress air and deliver it to the top of the main gasoline or other fuel supply tank, and that forces the gasoline from the main supply tank into an auxiliary tank placed above it, from which it flows to the carburetor, and from the carburetor as an explosive mixture, into the engine cylinder, to which my pressure fuel feeding apparatus is connected, as well as to the other cylinders of the engine.

Third. To provide a pressure feeding gasoline or other fuel apparatus for internal combustion engines, that automatically compresses air by a pumping mechanism that receives its operative power from the expansive force of the exhaust gases at the 35 time of the spark explosions of the gasoline or other fuel explosive mixture in one of the cylinders of the engine, and that conveys the air to the main fuel supply tank of the engine, and that is provided with a safety 40 valve that automatically regulates the air pressure in the fuel supply tank to that pressure best adapted to even pressure flow of the fuel to the carburetor.

I attain these objects by the mechanism 50 illustrated in the accompanying drawings, in which—

Figure 1 is a side elevation of my gasoline fuel pressure feeding apparatus, operatively connected to the main gasoline supply tank 55 and to a cylinder of an internal combustion engine.

Fig. 2 is a plan view of my gasoline pressure feeding apparatus for internal combustion engines, showing a small portion of its casing broken away to show the internal 60 construction of a part of it.

Fig. 3 is a section through the back flame preventing chambered casing of the pressure feeding apparatus.

Fig. 4 is a longitudinal, central section 65 through the air compressing pump portion of my gasoline pressure feeding apparatus. And

Fig. 5 is a longitudinal, central sectional view of the air compressing pump showing 70 slight variations and changes in some of its parts, and of its back flame preventing chambered casing.

Similar letters of reference refer to similar parts throughout the several views. 75

My invention has been especially designed to be attached to the already installed and operating internal combustion engines of automobiles, trucks, marine boats, flying machines, and especially to the engines of 80 tractors; and it is directly connected to one of the cylinders of the engines and also to their gasoline supply tank and to their carburetors; and the preferred arrangement and construction of my gasoline or other 85 pressure fuel feeding apparatus is as follows:

In Figures 1, 2, 3 and 4 I illustrate a different shaped air compressing pump than is shown in Figure 5, and there are slight 90 differences in construction between the two, but the general constructive features and arrangement of the several parts relative to each other is practically the same, while their operating function of compressing air 95 and forcing it into the main gasoline supply tank is the same.

As Figures 4 and 5 are complete sectional views, and as they show the two different arrangements of some of the parts of the 100 air compressing pumps through their piston cylinders, they will be described first, and the same reference numerals will be used for both of these views wherever the parts are alike or similar to each other. 105

The numeral 1, designates the casing of my complete air compressing pump, the principal difference being that the casing in Figure 4 is provided with a back fire preventing chambered casing 2, that is cast 110 on one side of the casing 1, while the casing in Figure 5 is provided with a T-shaped

casing 31, that is provided with a back firing tubular casing 2^A. Each of these back firing chambered members will be fully explained hereinafter.

5 The casings 1, of Figures 4 and 5, are provided with an air compressing chamber 3, which is provided with air inlet apertures 3^A, that extend into and through the casing 1.

10 The casing 1, of both Figures 4 and 5, is preferably cast integrally with a removable cover 4, of an auxiliary gasoline tank 5, although the cover may be removably secured to it if desired.

15 One end 6, of the casing is either provided with a reduced nipple portion 7, or with an interiorly threaded aperture 7^A, to which one end of a pipe 8, is connected. This pipe 8, is provided with any suitable 20 connecting fitting that can be threaded over the nipple 7, or threaded into a removable valve seat bushing 8^A, which is preferably inserted in the end of the casing 1, of Figure 4, rather than forming the valve seat 25 in the casing itself. The opposite end 9, of the pipe 8, is threaded into a threaded aperture 10, that is formed in the top portion of one of the cylinders 11, of the engine 12, just above the end of the upper stroke 30 of the engine's piston, which is not illustrated.

The threaded aperture 10, in the cylinder, is one of those that was originally made to receive a priming cup, but the priming cup 35 has been removed, and the end 9, of the pipe 8, is connected to it.

The engine 12, is provided with the commonly used gasoline supply tank 14, which I will call the main gasoline supply tank, 40 and a pipe 15, extends from the bottom of the main gasoline supply tank 14, to the bottom of the auxiliary tank 5, through which it extends upwardly within the tank 5, from its bottom by means of an extension pipe 16, that is connected to the pipe 15, at the bottom of the tank by suitable pipe and tank fittings. This pipe 16, extends from the bottom of the tank upwardly to close to the underside of its cover 4, and 45 the gasoline in the main gasoline supply tank 14, is forced up into the auxiliary tank 5, which is positioned above it, by compressed air, as will be fully described hereinafter.

To the bottom of the auxiliary tank I 55 cure one end of a pipe 17, the opposite end of which extends to and is connected to a carburetor 18, which is connected by a manifold 18^A, to the cylinder 11. The carburetor is positioned enough below the auxiliary 60 tank to allow the gasoline therein to flow readily from the auxiliary tank 5, to it.

The casing 1, of the air compressing cylinder 3, is preferably made about three and a half inches long and it is preferably only 65 about seven-eighths of an inch in diameter,

and to facilitate making connections, its opposite ends 19, are preferably made of hexagon form.

The air compressing chamber 3, is preferably about a half inch in diameter, and extends throughout its length to close to its nipple end 7, where it is intersected by a small aperture 7^A, that is formed through the axial center of the nipple 7, of Figure 5, or through the valve seat plug 8^B. The 70 intersecting shoulder of the cylindrical chamber 3, and the axial aperture through the terminal nipple 7, or at the end of the bushing 8^A, is provided with a valve seat 8^C, and a ball valve 20, (which is only shown 75 in Figure 5,) which is normally held against its seat by a reciprocating piston 21, that is actuated in one direction of its reciprocal movement by an expansion spring 22; the piston after passing the air inlet port 3^A 80 acts to compress the air that freely enters the chamber 3, through the air inlet apertures 3^A, that are formed through the shell of the casing 1.

The entrance to the rear end of the cylinder bore of the air compressing chamber 3, is interiorly threaded, and an adjustable plug 23, is threaded into it, and the rear end of the spring 22, bears against a shoulder 22^A, formed on it. The outer end of 90 which is provided with a wrench receiving end 24, by which it may be adjustably turned in the casing. This plug 23, is provided with axial apertures 25 and 26, of different diameters, which extend in end to end alignment entirely through it. The largest aperture 25, is at its outer end, and it contains a tapered valve seat 27, at its inner end, against which a ball valve 28, that controls the aperture 26, is normally held by an 95 expansion tension spring 29, the outer end of which abuts against the end of a reduced threaded nipple portion 30, that is formed on the end of a T-shaped safety valve casing 31, in Figure 5, and against a disk 31^A, 100 in Figure 4, which is secured in the outer end of the plug 23. This safety valve casing 31, which is only shown in Figure 5, contains an axial bore of two different diameters, 32 and 33, and an air outlet hole 105 34, is formed through the casing into the largest aperture 32, close to the tapered shoulder at the junction of these two apertures, which forms a seat for a ball valve 35, and an expansion tension spring 36, that 110 is adjustably held against the ball valve by a plug 37, that is adjustably threaded into the end of the aperture 32, of the casing 31. This safety valve casing 31, comprises a small T-shaped casting that has a 115 depending nipple portion 38, which is provided with an axial aperture 39, and the terminal end of the nipple is connected to one end of the back fire preventing chambered casing 2^A, and the opposite end of the 120

125 depending nipple portion 38, which is provided with an axial aperture 39, and the terminal end of the nipple is connected to one end of the back fire preventing chambered casing 2^A, and the opposite end of the 130

back fire preventing chambered casing 2^A, is threaded to one end of a pipe 40, in Figure 5, and this pipe 40, is also connected in Figure 1, to the lower end 41, of the back fire preventing chambered casing 2, and the opposite end of the pipe 40, extends to and is connected to the top portion of the main gasoline supply tank 14.

The piston 21, is provided with oil 10 grooves 21^A, and the front end of the piston shown in Figure 5, is provided with a countersunk recess that fits partially over the ball valve 20. This ball valve 20, is dispensed with in Figure 4, and instead of 15 it, the end of the piston is taper pointed to fit against the valve seat 8^C. The rear end of the spring 22, bears expansively against a shoulder 41, formed on the inner end of the plug 23. Consequently this expansion 20 tension spring 22, holds the piston normally under a constant resilient pressure that normally holds the inner end of the aperture 7^A, closed so that no gases or air can escape past it and flow back into the 25 cylinders 11, through the pipe 8, when the piston thereof makes its downward strokes, as will be fully explained hereinafter. Consequently, the piston 21, can be used either with or without the ball valve 20, as 30 described.

The air compressing cylinder, with its two valves and the piston and the springs that actuate them in one direction of their movement, I term an air compressing pump, 35 as it intermittently pumps air on top of the gasoline in the main gasoline supply tank 14.

The back fire preventing chambers 2 and 2^A, are arranged as follows: The air 40 compressing pump construction of Figures 2, 3 and 4, and its back fire preventing chambered casing 2, represents my preferred construction, as it is especially adapted for use on engines of high powered automobile cars, 45 trucks, tractors, marine and flying machine engines, although the air pump illustrated in Figure 5, and its back firing preventing chambered casing may be used if desired. Its smaller back firing preventing casing 50 and pressure escaping mechanism adapts it more for use on the general sizes of smaller motors of cars and trucks than the larger sizes shown in Figures 2, 3 and 4. The principle of construction and operation, 55 however, is substantially the same in both devices.

The chambered casing 2, is larger in diameter than the chambered casing 2^A, but each is provided with a number of disks of 60 fine wire gauze screens 42, of which there are five shown in each of the chambers 43, of the casings 2 and 2^A, and they are held in place by turned-up or cupped edges 44, that fit against the wall of the chamber. 65 The lower screen disk rests on a shoulder

45, and the other four disk screens rest on top of each other at their edges.

In the air compressing pump illustrated in Figures 1 and 4, the air, as it is compressed by the piston 21, flows from the 70 large axial aperture 25, which contains the spring 29, through radial holes 46, into and through a passageway 47, that is formed in the casings 1 and 2, into the chamber 43, of the casing 2, instead of through the safety 75 T-shaped member 31, of Figure 5, and instead of the pressure relief valve 35, and its spring 36, in Figure 5, the chambered casing 2, is provided with a removable cap 48, that is secured to the casing by screws 48^A, 80 and that is provided with an upwardly projecting hub 49, that contains a threaded aperture, in which an adjustable plug 50, is threaded. The plug 50, is provided with an axial aperture in which a valve stem 51, fits slidingly, on the lower end of which a flat thin beveled edge valve 52, that sets on a bevel edged valve seat that is formed in the upper edge of the chamber 43, is placed. The upper end of the valve stem is provided 90 with a screw driver receiving slot 53, by which the valve can be turned and ground on its seat to insure that it will seat much more evenly than it would if left in a stationary position thereon.

On the valve stem 51, below the end of the plug 50, and between it and the top of the valve 52, an expansive coiled spring 54, is placed, which normally holds the valve 52, against its seat, by its expansive resilient 100 pressure against the valve.

The bottom of the cap 48, of the chambered casing 2, is provided with radial grooves 55, which permits the excess air pressure that flows into the chamber 2, 105 from the air compressing chamber 3, of the casing 1, to escape to the atmosphere, where it is under pressure to lift the flat valve 52. This adjustable valve mechanism with its air escaping grooves 55, is the equivalent of the ball valve 35, and its spring 36, and the air escaping apertures 34, in the T-shaped casing 31.

The operation of my pressure fuel feeding apparatus is as follows:

As each and every spark explosion takes place at the upper end of the cylinders 11, enough exhaust gas is forced by the compressive explosion in the cylinder through the pipe 8, and the aperture 7^A, of the nipple 7, of the casing 1, to move the piston 21, backward against its spring 29, which compresses air in the chamber 3, that enters it through the air inlet apertures 3^A, which are positioned in the casing 1, at the rear end of piston. Consequently, the interior of the chamber 3, of the air compressing cylinder 2, is always normally filled with air that flows freely into it through the apertures 3^A, in the shell of its casing, and at each ex-

1. A plosion stroke of the engine of the cylinder 11, a small quantity of exhaust gases is driven through the pipe 8, and the aperture 7^A, against the piston 21, which is driven violently back from its seat against its spring 22, and the piston 21, on this violently quick backward stroke compresses the air in the chamber 3, and forces it through the aperture 26, in the plug 23, through which it is forced against the ball valve 28, that is moved back against its spring 29, allowing the compressed air to flow into the apertures 33 and 39, in the T-shaped safety valve's casing 31, from which it flows through the pending tube casing 2^A, containing gauze wire screen 42, which prevents any possibility of flame from the explosion in the cylinder 11, from moving through the pipe 40, to the main fuel tank 14. The compressed air, however, flows through the pipe 40, into the tank 14, and exerts a pressure on the top surface of the gasoline supply therein, that forces it to flow up through the pipes 15 and 16, into the top of the auxiliary gasoline supply tank 5, and from this auxiliary tank the gasoline flows also by pressure, through the pipe 17, to the carburetor 18, through which it passes and flows from it through the manifold 18^A, as explosive gas into the cylinder 11, of the engine 12. Consequently, air is pumped intermittently at each explosive stroke of the piston in the cylinder 11; as the pipe 8, of my pump is connected to only one of the four or more cylinders the engine motor may have, but the explosions in this one cylinder are sufficient to keep the main gasoline supply tank 14, filled with an air pressure that forces an abundant supply of gasoline up into the auxiliary tank 5, and more air will be compressed and pumped into the main gasoline supply tank than is necessary, for when the air pressure is too great, the gasoline is forced too fast into the auxiliary tank and from it into the carburetor, and it is consequently necessary to use the tension of the spring 36, of the safety ball valve 35, so that it will let the air pressure escape through the aperture 34, in Figure 5, to maintain only that pressure which will force the gasoline to feed properly from the main gasoline tank to the auxiliary tank, and from it to the carburetor.

My invention provides a positive and reliable pressure fuel feeding apparatus for internal combustion engines requiring no attention or assistance from the driver, which removes the necessity of having an auxiliary unit such as the commonly used hand or manually operated pump required in present systems in use, for producing pressure upon the main gasoline tank, when the motor has been stopped and left standing in an inoperative condition for any length of time, and while I have illustrated its preferred construction and arrangement, I do

not wish to be limited to it, as changes may be made without departing from the spirit of my invention.

Having described my invention, what I claim as new and desire to secure by Letters Patent, is:

1. A pressure feeding apparatus for internal combustion engines, comprising a casing having an apertured member connected to the cylinders of said engine at its fuel explosion end, and provided with an air compressing chamber, a valve seat in said chamber at the passage leading to said cylinder, and means including a piston reciprocally mounted in said chamber and bearing against said valve seat for controlling said passage.

2. A pressure feeding apparatus for internal combustion engines, comprising a casing having an apertured member connected to the cylinders of said engine at its fuel explosion end, and provided with an air compressing chamber, a valve seat in said chamber, controlling the passage leading to said cylinder, a spring actuated reciprocating member in said chamber arranged to control said valve seat, and an adjustable plug in said chamber arranged to adjust the pressure of said spring against reciprocating member.

3. A pressure feeding apparatus for internal combustion engines, comprising a casing having an apertured member connected to the cylinders of said engine at its fuel explosion end, and provided with an air compressing chamber, and a passageway from said cylinder into said chamber; with a reciprocating member in said chamber arranged to control said passageway, and an adjustable plug in said chamber arranged to adjust the pressure of said spring against said piston, said casing being provided with air inlet apertures between said reciprocating member and said plug.

4. A pressure feeding apparatus for internal combustion engines, comprising a casing having an apertured member connected to the cylinders of said engine at its fuel explosion end, and provided with an air compressing chamber, a valve in said chamber controlling the passage leading to said cylinder, a spring actuated piston reciprocally mounted in said chamber and bearing against said valve, and an adjustable plug in said chamber arranged to adjust the pressure of said spring against said piston, said casing being provided with air inlet apertures between said piston and said plug, said plug being provided with an axial aperture, and a spring controlled valve seated in said aperture.

5. A pressure feeding apparatus for internal combustion engines, comprising a casing having an apertured member connected to the cylinders of said engine at its fuel ex-

5 plosion end, and provided with an air compressing chamber, a valve in said chamber controlling the passage leading to said cylinder, a spring actuated piston reciprocally mounted in said chamber and bearing against said valve, and an adjustable plug in said chamber arranged to adjust the pressure of said spring against said piston, said casing being provided with air inlet apertures between said piston and said plug, said plug being provided with an axial aperture, and a spring controlled valve seated in said aperture, and an axial aperture T-shaped casting provided with an outlet aperture and provided with a pressure relief valve in its axial aperture. 10 6. A pressure feeding apparatus for internal combustion engines, comprising a casing having an apertured member connected to the cylinders of said engine at its fuel explosion end, and provided with an air compressing chamber, a valve in said chamber controlling the passage leading to said cylinder, a spring actuated piston reciprocally mounted in said chamber and bearing against said valve, and an adjustable plug in said chamber arranged to adjust the pressure of said spring against said piston, said casing being provided with air inlet apertures between said piston and said plug, said plug being provided with an axial aperture, and a spring controlled valve seated in said aperture, and an axial apertured T-shaped casting provided with an outlet aperture and provided with a pressure relief valve in its axial aperture, said engine being provided with a main supply tank, and said casing being provided with an axially apertured depending nipple member, and a pipe connected at one end to said nipple member and to the top of the said main fuel supply tank. 15 7. A pressure feeding apparatus for internal combustion engines, comprising a casing having an apertured member connected to the cylinders of said engine at its fuel explosion end, and provided with an air compressing chamber, a valve in said chamber controlling the passage leading to said cylinder, a spring actuated piston reciprocally mounted in said chamber and bearing against said valve, and an adjustable plug in said chamber arranged to adjust the pressure of said spring against said piston, said casing being provided with air inlet apertures between said piston and said plug, said plug being provided with an axial aperture, and a spring controlled valve seated in said aperture, and an axial apertured T-shaped casting provided with an outlet aperture and provided with a pressure relief valve in its axial aperture, said engine being provided with a main supply tank, and said casing being provided with an axially apertured depending nipple member, and a pipe connected at one end to said nipple member and to the top of the said main fuel supply tank. 20 8. A pressure feeding apparatus for internal combustion engines, comprising a casing having an apertured member connected to the cylinders of said engine at its fuel explosion end, and provided with an air compressing chamber, a valve in said chamber controlling the passage leading to said cylinder, a spring actuated piston reciprocally mounted in said chamber and bearing against said valve, and an adjustable plug in said chamber arranged to adjust the pressure of said spring against said piston, said casing being provided with air inlet apertures between said piston and said plug, said plug being provided with an axial aperture, and a spring controlled valve seated in said aperture, and an axial apertured T-shaped casting provided with an outlet aperture and provided with a pressure relief valve in its axial aperture, said engine being provided with a main supply tank, and said casing being provided with an axially apertured depending nipple member, and a pipe connected at one end to said nipple member and to the top of the said main fuel supply tank, an auxiliary fuel holding tank above said main fuel tank, means for securing said air compressor to said auxiliary tank, and a pipe connected at one end to the bottom of said main fuel supply tank, and extending to and through and up into the top portion of said auxiliary tank, and a pipe secured to the bottom of said auxiliary tank and extending to said carburetor. 25 9. A pressure feeding apparatus for internal combustion engines, comprising a casing having an apertured member connected to the cylinders of said engine at its fuel explosion end, and provided with an air compressing chamber, a valve in said chamber controlling the passage leading to said cylinder, a spring actuated piston reciprocally mounted in said chamber and bearing against said valve, and an adjustable plug in said chamber arranged to adjust the pressure of said spring against said piston, said casing being provided with air inlet apertures between said piston and said plug, said plug being provided with an axial aperture, and a spring controlled valve seated in said aperture, and an axial apertured T-shaped casting provided with an outlet aperture and provided with a pressure relief valve in its axial aperture, said engine being provided with a main supply tank, and said casing being provided with an axially apertured depending nipple member, and a pipe connected at one end to said nipple member and to the top of the said main fuel supply tank. 30 10 11 12 13 14 15 16 17 18 19 20 21 22 23 24 25 26 27 28 29 30 31 32 33 34 35 36 37 38 39 40 41 42 43 44 45 46 47 48 49 50 51 52 53 54 55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

- 8
- to the top of the said main fuel supply tank, an auxiliary fuel holding tank above said main fuel tank, means for securing said air compressor to said auxiliary tank, and a 5 pipe connected at one end to the bottom of said main fuel supply tank, and extending to and through and up into the top portion of said auxiliary tank, and a pipe secured to the bottom of said auxiliary tank and extending to said carburetor, and means within 10 in the air compressing chamber of said air pumping cylinder for preventing back firing of the explosions in the cylinder of said engine to which said air pump is attached.
- 15 10. A fuel pressure feeding apparatus for gasoline or other explosive fuel used in the cylinders of internal combustion engines, provided with a carburetor comprising an intermittent pump mechanism connected to 20 one of the cylinders of said engine, and an automatically operated pressure regulating and safety valve, and arranged to pump air into the main fuel supply tank of the engine, and means for forcing the fuel from 25 the main supply tank and feeding it to the carburetor of the engine.
11. A pressure feeding apparatus for internal combustion engines, comprising a casing having an apertured member connected 30 to the cylinders of said engine at its fuel explosion end, and provided with an air compressing chamber, a valve in said chamber controlling the passage leading to said cylinder, a spring actuated piston reciprocally mounted in said chamber and bearing 35 against said valve, and an adjustable plug in said chamber arranged to adjust the pressure of said spring against said piston, said casing being provided with air inlet apertures between said piston and said plug, said 40 plug being provided with an axial aperture, and a spring controlled valve seated in said aperture, said axial apertures being of two different diameters, a spring actuated ball 45 valve at the junction of the two diameters, and an adjustable plug threaded into the 50 end of the valve aperture and arranged to bear against said valve's actuating spring, whereby the said valve may be regulated to automatically regulate the pressure of the 55 air being compressed in said casing's chamber and pumped into said main fuel supply tank by said reciprocating piston actuated by the explosive force of the explosions of the explosive mixture in the cylinder to which said air compressor is attached.
12. A pressure feeding apparatus for internal combustion engines, comprising a casing having an apertured member connected 60 to the cylinders of said engine at its fuel explosion end, and provided with an air compressing chamber, a valve in said chamber controlling the passage leading to said cylinder, a spring actuated piston reciprocally mounted in said chamber and bearing 65 against said valve, and an adjustable plug in said chamber arranged to adjust the pressure of said spring against said piston, said engine being provided with a main gasoline or other fuel holding tank, and with a carburetor; of an auxiliary tank provided with a removable cover positioned above said main fuel supply tank, means for securing said air compressing cylinder to the cover of said auxiliary tank, said carburetor piping 70 connected to the bottom of said auxiliary tank and extending to said carburetor, and means including a pipe for conveying the air compressed in said chamber to the top of said main fuel supply tank, whereby a small portion of the explosive force of the intermittent explosions of the explosive mixture in the cylinder to which said air compressing and pumping cylinders is attached, compresses air in said cylinder and pumps 75 it into the top of said main fuel supply tank, from which it is forced by said air pressure up into said auxiliary tank, from which it flows to said carburetor from which the explosive mixture flows into the cylinders, said 80 air compressing and pumping cylinder is attached to.
13. In a gasoline or other explosive fluid pressure feeding apparatus of the carburetors and cylinders of internal combustion 95 engines, the combination of a cylinder of the engine, and the main fuel supply tank, with an air compressing pump connected at one end to the fuel exploding part of said cylinder and arranged to force air into said main fuel supply tank, and provided with a back fire stopping and preventing chambered casing, the chamber of which is provided with a plurality of gauze wire screens, and with a spring controlled pressure relief valve. 100
14. In a gasoline or other explosive fluid pressure feeding apparatus for the carburetors and cylinders of internal combustion engines, the combination of a cylinder of the engine, and the main fuel supply tank, with an air compressing pump connected at 110 one end to the fuel exploding part of said cylinder and arranged to force air into said main fuel supply tank, and provided with a back fire stopping and preventing chambered casing, the chamber of which is provided with a plurality of gauze wire screens, and with a spring controlled pressure relief valve, an auxiliary fuel holding tank positioned above said main fuel supply tank 115 and connected thereto, to receive fuel therefrom, and a carburetor connected operatively to said auxiliary tank and to said cylinder, whereby said pump receives explosive pulsations from said cylinder and compresses 120 and forces air into said main fuel tank and forces the fuel from it up into said auxiliary tank, from which it flows by pressure into said carburetor, and from it into said cylinder. 125
- 150

15. In a gasoline or other explosive fluid pressure feeding apparatus for the carburetors and cylinders of internal combustion engines, the combination of a cylinder of the engine, and the main fuel supply tank, with an air compressing pump connected at one end to the fuel exploding part of said cylinder and arranged to force air into said main fuel supply tank, and provided with a 10 back fire stopping and preventing chambered casing, the chamber of which is provided with a plurality of gauze wire screens, and with a spring controlled pressure relief valve, said screens being arranged across 15 said chamber in the path of the compressed air flowing into said main fuel supply tank, and said pressure relief valve comprising a disk-shaped valve seated in said chamber, an adjustable plug threaded in said chamber, a valve stem on said valve slidably 20 mounted on said plug, and an expansive pressure spring mounted on said valve stem between said plug and said disk valve, and arranged to normally hold said disk valve closed against its seat in said chamber casing, and against the air pressure therein, and air escaping apertures extending through said casing from said chamber above the opening movement of said valve.

In testimony whereof I affix my signature 30 in presence of two witnesses.

PHILLIP ALEXANDER KINZIE.
